UNITED STATES PATENT OFFICE.

HARVEY L. JEWELL, OF BANGOR, MAINE.

LANTERN.

SPECIFICATION forming part of Letters Patent No. 389,083, dated September 4, 1888.

Application filed March 12, 1887. Serial No. 230,603. (No model.)

To all whom it may concern:

Be it known that I, HARVEY L. JEWELL, a citizen of the United States, residing at Bangor, in the county of Penobscot and State of Maine, have invented new and useful Improvements in Lanterns; and I do hereby declare that the following is a full, clear, and exact description of the invention, which will enable others skilled in the art to which it appertains to make and use the same.

My invention relates to improvements in that class of lanterns in which the globe is held in position by a sliding frame, whereby it can be raised from the burner-cone for exposing the latter in order to facilitate the operation of lighting and trimming the wick and extinguishing the flame.

My improvements consist of certain details of construction hereinafter described, shown in the drawings, and pointed out in the claims.

In the accompanying drawings, consisting of two sheets, Figure 1 is an elevation of a lantern provided with my improvements, the globe-frame being lowered. Fig. 2 is a similar view with the globe-supporting frame raised. Fig. 3 is an elevation of the upper part of the lantern at right angles to Fig. 1, showing also in dotted lines the globe in the position in which it engages the free ends of the spring-arms to press them apart. Fig. 4 is an elevation of a lantern, showing a different application of my lifting devices. Fig. 5 is a front elevation of the lower part of the globe-supporting frame and supporting-disk, showing the disk partly tilted or inclined, as it is when applying and removing the globe from the frame. Fig. 6 is a plan view showing the spring-arms separated for the insertion of the globe. Fig. 7 is a plan view of the devices constituting the catch which holds the globe-frame depressed.

In the drawings, A represents the base of the lantern; B B, the side tubes; C, the central-draft tube; and D, the bell or cap of the globe-supporting-frame, having a vertical movement on the tube C.

E represents the burner-cone, F the tilting globe-supporting disk, and G the globe.

H is the bilateral elastic double-wire globe holder and guide attached to the bell D, said holder and guide being composed of the wires

i', one passing above, the other below, the rib on the globe, as shown in the drawings, thus effectually preventing any displacement of the globe in a vertical direction. Said holder 55 being constructed in two parts (right and left sides) secured at the rear to the globe-supporting frame, embracing the sides of the globe, and being horizontally elastic and movable, it readily admits the globe between its free ends, 60 while the wires above and below the rib guide it into its proper position.

I represents the shouldered spring-stop holding the globe-supporting frame in its lower position.

J is the vertical depressing rod and guard. k represent the side wires or rods of the globe-supporting frame attached to the bell D and turned in at their ends to support the disk F pivotally, and being free to slide in the 70 guides or loops l l, secured to the side tubes, B B. m m are coiled springs, preferably surrounding the rods or wires k, between the loop l and either the lower or upper ends of said wires.

n is a thimble attached to the bell D, to which is secured the spring-stop I and the rod J, said thimble having a vertical movement on the tube C. o is a disk attached to the upper end of the tube C, having openings through 80 which the stop I and the rod J slide.

My device for automatically raising the globe-supporting frame accomplishes the same result by the use of a pull or push spiral spring, preferably coiled about the side wires or rods, 85 k. When used as a pull-spring, the ends are respectively attached to the loops l and the lower part of the rods k, as shown in Fig. 1. When used as a push-spring, the ends bear respectively upon the loops l and the small disks 90 attached to the upper part of the rods k, as shown in Fig. 4.

When the globe-supporting frame is to be raised for the purpose of lighting or trimming the wick, a slight inward pressure upon the 95 upper part of the spring-stop I disengages the shoulder p from the under side of the disk o, allowing said stop to slide in a vertical direction through the slot in the disk o, thereby allowing the globe-supporting frame to be moved 100 vertically by the action of the springs, thus obviating the necessity of raising the globe-

frame or of holding it in its upper position while in the act of lighting the lantern.

The operation of my invention is as follows, supposing the globe to be down, as in Fig. 1: 5 It being desired to raise the same, the forefinger is placed upon the flat bearing at the upper end of the rod J, and the stop I is pressed inward by the thumb until its shoulder *p* is disengaged from the disk *o*. The globe holder 10 and globe will immediately spring upward, such movement being governed by the pressure of the finger, so that the globe may not be broken or thrown out of its holder. The wick having been trimmed, lighted, or extinguished, 15 as may be the case, the pressure is applied to the flat top of the rod J, and the holder and globe forced downward until the stop I springs out, with its shoulder *p* under the disk *o*, when the hand may be removed and the parts will 20 remain securely held in the position shown in Fig. 1. To remove the globe, the two parts of the wire frame H are pressed apart and the upper end of the globe passed out between their ends. As the globe is thus swung out of 25 a vertical line, it continues to rest upon the disk F, which accordingly turns upon the horizontal pivots formed by the ends of wires *k* to accommodate the position of the globe. When the globe has cleared the frame H, it is 30 removed from said disk. In inserting the globe it is first placed in an inclined position upon the disk F, and then tilted upward till the bead of the globe enters between the ends of the frame H, and having first pressed said 35 ends outward, is finally clasped and secured by the frame as its parts spring back into place.

The particular construction of the globe-supporting frame herein described and shown is not material so far as the catch is concerned, 40 and my device for automatically holding said frame may be applied to frames of various forms of construction with the same effect.

What I claim, and what I desire to secure by Letters Patent, is—

1. In a lantern, the combination, with the 45 globe supporting frame, of the double horizontally-operating spring-arms secured thereto and having portions for engaging the globe both above and below its bead, said spring-arms being free at and having an opening 50 between their forward ends, and the tilting plate F, for supporting the lower end of the globe and adapted to oscillate therewith as the globe is turned from an inclined to a vertical position, thereby insuring that the proper part 55 of the globe shall meet and enter between the said arms, substantially as set forth.

2. In a lantern, the combination, with the globe-holding frame and as a means for securely holding the upper end of the globe, of 60 the double horizontally-operating spring-arms *i i'*, secured at the rear to the globe-holding frame, free and separable at and having an opening between their forward ends, and having 65 portions for engaging the bead of the globe on both its upper and lower sides, substantially as set forth.

3. In a lantern, the combination, with the main frame having the central tube, C, of the globe-holding frame sliding on said tube and 70 having the side rods, *k*, guides *l l'*, engaging said rods, springs *m m* for pressing the globe-frame upward, the push-rod J, carried by the globe-frame, the spring-stop I, also carried by the globe-frame and having the shoulder *p*, 75 and the disk *o*, mounted on the tube C, having a guiding-opening for said push-rod, a slot for and inclosing the said spring-stop and adapted to be engaged by the shoulder of the latter, substantially as described.

HARVEY L. JEWELL.
